UNITED STATES PATENT OFFICE.

JAMES L. MCQUARRIE, OF MONTCLAIR, NEW JERSEY, AND CHARLES L. GOODRUM, OF NEW YORK, N. Y., ASSIGNORS TO WESTERN ELECTRIC COMPANY, INCORPORATED, OF NEW YORK, N. Y., A CORPORATION OF NEW YORK.

TELEPHONE-EXCHANGE SYSTEM.

1,393,558.

Specification of Letters Patent.

Patented Oct. 11, 1921.

Application filed August 7, 1919. Serial No. 315,827.

To all whom it may concern:

Be it known that we, JAMES L. MCQUARRIE and CHARLES L. GOODRUM, citizens of the United States, residing at Montclair, in the 5 county of Essex and State of New Jersey, and New York, in the county of New York and State of New York, respectively, have invented certain new and useful Improvements in Telephone-Exchange Systems, of 10 which the following is a full, clear, concise, and exact description.

This invention relates to improvements in telephone exchange systems and has particular reference to circuit arrangements for various switches therefor.

An object of the invention is to provide a controlling mechanism for selector switches which may be temporarily utilized for controlling any one of a plurality of switches 20 and which is selected after one of the switches has been seized.

Another object is to control the operation of any one of a plurality of final selector or connector switches by a common mechanism 25 which is associated with the switch to be operated after the same has been seized and which remains in association therewith for the duration of a call.

The inventive idea involved is capable of 30 receiving a variety of expressions one of which, for the purpose of illustrating the invention, is shown in the accompanying drawings; but it is to be expressly understood that drawings are employed merely 35 for the purpose of facilitating the description of the invention as a whole and not to define the limits thereof, reference being had to the appended claims for this purpose.

In the drawings, Figure 1 is a diagrammatic view of a selector switch and circuits employed in connection therewith; Fig. 2 is a similar view of a final selector or connector switch.

The system of the present invention has 45 been shown as including a selector switch A and a connector switch B, but it will be understood that the number of switches necessary in establishing a call may be increased to conform with the capacity of an exchange.

Briefly, a number of selector switches A are provided with a mechanism C associated with a multipled bank of stationary contacts and operated by stepping means responsive to an electrical condition applied to

the particular switch seized, whereby a 55 group of plungers included in said mechanism are positioned before and then engaged with a group of contacts of said bank which connect the incoming line with the seized switch. The operation of the switch is then 60 controlled by a mechanism shown at the left of Fig. 1 which is common to a number of switches but unavailable to any other but the seized switch during the actual operation thereof. When the switch has extended the 65 calling line, mechanism C is restored to normal and together with said common means is again made available for another operation.

The operation of mechanism D of the connector switch shown in Fig. 2, and the common mechanism at the left of said figure is 70 the same as in Fig. 1 with the exception that said mechanisms are not made available to another switch until switch B has returned to normal at the termination of a call.

It is now believed that the following detailed description will enable those skilled in the art to fully understand the invention.

When a subscriber at substation 1 removes his receiver from its switchhook, a circuit 80 is closed to operate a line switch or finder (not shown) to select a trunk leading to an idle selector switch A and upon engaging the terminals of said trunk a ground at said line or finder switch is applied to conductor 2 85 in a manner well known in the art. A holding circuit is then closed for release magnet 3 individual to the selector A, which circuit extends from grounded battery, winding of magnet 3 and conductor 2 to ground. Magnet 3 energizes and remains in this condition until the ground is removed from conductor 2 by the return of the line or finder switch to normal position. When magnet 3 energizes, a self-interrupting circuit is established for stepping magnet 4 extending from 90 grounded battery, winding, armature and back contact of said magnet, right armature and back contact of test relay 5, side-switch wiper 4' in position 1, outer left armature 95 and back contact of relay 6, inner front contact and armature of magnet 3 to ground. Upon each energization of the magnet 4, pawl 7 operates to rotate shaft 8 and the

plunger carrying frame 9 supported thereby. 100 A finder brush 10 also carried by the shaft 8 is stepped from its normal position and passes over a row of terminals 11 until the 105

terminal individual to the particular selector switch seized is found. When the brush engages terminal 11 to which the conductor 12 is connected, a circuit is established from 5 test relay 5, extending from grounded battery, winding of said relay, side-switch wiper 13 in position 1, brush 10, terminal 11, conductor 12, inner left armature and back contact of relay 6, outer front contact and armature 10 of magnet 3 to ground. Relay 5 energizes and locks up through wiper 13 in positions 1 and 2 to ground at the inner left armature and front contact of said relay. At 15 its right armature relay 5 breaks the self-interrupting circuit of magnet 4 and brings the plunger carrying frame 9 to a stop before the row of contact springs individual to the selector switch A. Energization of relay 5 also closes a circuit for plunger magnet 14 20 traceable from grounded battery, winding of said magnet, outer left armature and front contact of relay 5 to ground. Magnet 14 operates to move the frame 9, against the tension of the springs 15, until the plungers carried by said frame engage their respective contact springs. At this time a circuit is 25 closed for the line relay 16 common to the group of selector switches, similar to switch A, said circuit extending from grounded battery, right winding of relay 16, plunger 17, spring contact 18, lower side of the subscriber's line, the apparatus of substation 1, the upper side of the subscriber's line, contact spring 19, plunger 20 and left winding 30 of relay 16 to ground. Relay 16 energizes and closes a circuit for slow-to-release relay 21, extending from grounded battery, winding of said relay, front contact and armature of relay 16 to ground. Engagement of 35 plunger 39 with contact 38 closes an energizing circuit for relay 6 extending to ground through wiper 37 in position 1. Relay 6 then locks up through its right winding, front contact and right armature to 40 ground on the conductor 2. By attracting its outer left armature, relay 6 prevents the extension of the ground at the armature of magnet 3 to any other selector switch after wiper 4' has moved into position 2. Wiper 4' in position 2 of the side switch extends 45 the starting conductor to the next idle switch C so the seizure of another selector and the energization of its magnet 3 will close the circuit of the motor magnet 4 of the switch 50 C to cause the same to hunt for the seized selector. Switch A is now in condition to receive a series of impulses from substation 55 1 corresponding to the first digit of the wanted line.

60 Deenergization of relay 16 in response to the first impulse transmitted, establishes a circuit for slow-to-release relay 22, extending from grounded battery, winding of said relay, front contact and armature of relay 65 21 and back contact and armature of relay

16 to ground. Relay 22 energizes and, together with relay 21, remains in this condition during the transmission of a series of impulses. Energization of relay 22 establishes a circuit for escape magnet 23 extending from grounded battery, left winding of magnet 23 and front contact and inner armature of relay 22 to ground. Energization of magnet 23 at this time has no effect upon the side switch which it controls. In response to each deenergization of relay 16 due to the impulses transmitted, a circuit is also closed for primary stepping magnet 24 of switch A extending from grounded battery, winding of said magnet, contact 80 spring 25, plunger 26, side-switch wiper 27 in position 1, front contact and armature of relay 21 and back contact and armature of relay 16 to ground. Magnet 24 operates to step brushes 28, 29 and 30 of switch A in 85 a group selecting movement.

At the termination of the series of impulses, relay 16 remains energized and opens the circuit for slow-to-release relay 22 which, after an interval of time, releases. Deenergization of relay 22 opens the previously described circuit for escape magnet 23 which releases and in so doing moves the side switch wipers into position 2. Another circuit is immediately established for escape 90 magnet 23, extending from grounded battery, right winding of said magnet back contact and outer armature of relay 22, plunger 31, contact spring 32, primary off-normal contact 33 which closed upon the 95 first step of the brushes of switch A, and secondary off-normal contact 34 to ground. Escape magnet 23 energizes in this circuit but in so doing does not affect the side switch wipers. When the side switch wipers move into position 2, a self-interrupting circuit is established for secondary stepping magnet 35, which circuit extends from grounded battery, winding, armature and back contact of magnet 35, contact spring 36, 100 plunger 80 and side switch-wiper 37 in position 2 to ground. Each energization of the magnet 35 operates to step the brushes 28, 29 and 30 over the terminals of the selected group to hunt for an idle trunk therein. The first step of the brushes of switch A in the trunk hunting operation opens the secondary off-normal contact 34 and thus breaks the circuit for escape magnet 23 but 105 this magnet does not deenergize as long as 110 the brushes of switch A engage terminals of busy trunks, this condition being denoted by ground on the test terminals thereof. Therefore, during the passage of brushes of the switch A, over terminals of busy 115 switches, an energizing circuit for escape magnet 23 will be maintained through test brush 30 instead of primary and secondary off-normal contacts 33 and 34. When brush 30 engages a terminal upon which there is no 120

125 130

ground, escape magnet 23 will deenergize and so doing move side switch wipers from position 2 into position 3, thus permanently opening the self-interrupting circuit of secondary stepping magnet 35 and the brushes 28, 29 and 30 of switch A come to rest on the terminals leading to an idle connector switch. Side switch wiper 13, in moving from position 2 to position 3, opens the locking circuit for relay 5 which then releases and in so doing breaks at its outer left armature the circuit for magnet 14. Deenergization of this magnet permits the returning of plunger carrying frame 9 to its normal position under the influence of the springs 15 and thus removes the several plungers from engagement with their respective contact springs. The return to normal of contact springs 18, 19 and 32 extends the subscriber's line to the next succeeding switch. Release of relay 5 also closes a self-interrupting circuit for magnet 4 extending from grounded battery, winding, armature and back contact of said magnet, right armature and back contact of relay 5 and off-normal contact 40 to ground, said contact having been closed when the previously described circuit for magnet 4 was established to rotate shaft 8. Magnet 4 now operates to return frame 9 and finder brush 10 to normal position, whereupon this apparatus will be in condition to extend another call.

If, during the operation of the switch A, and while the side switch wipers are in positions 2 or 3, the subscriber at substation 1 abandons the call by replacing his receiver upon its switchhook, the circuit for line relay 16 is opened and this relay releases its armature. In so doing, the circuit for slow-to-release relay 21 is also opened but before this relay can retract its armature, a circuit is established for release magnet 41 extending from grounded battery, winding of said magnet, side-switch wiper 27 in position 2 or 3, front contact and armature of relay 21 and back contact and armature of relay 16 to ground. Release magnet 41 operates to return the side switch wipers to normal. Removal of ground from the conductor 2 by the return of the line or finder switch (not shown) causes the release of relay 6 and magnet 3 which then restores brushes 28, 29 and 30 to normal position. The switch is now ready for another operation.

Let it now be assumed that brushes 28, 29 and 30 of switch A engage terminals of the trunk leading to connector switch B, as shown in Fig. 2. The ground upon the release conductor 2 is now extended through the brush 30 to conductor 42 of connector switch B which results in the energization of release magnet 43 thereof. By attracting its armature, the magnet 43 establishes a circuit for stepping magnet 44 extending from grounded battery, winding, armature and back contact of said magnet, right armature and back contact of test relay 45, side-switch wiper 45' in position 1, outer armature and back contact of relay 50, inner front contact and armature of magnet 43 to ground. Magnet 44 operates in the same manner as described in connection with magnet 4 to rotate shaft 46, the plunger carrying frame 47 and finder brush 48 until the latter engages the terminal 49 individual to the switch B. A circuit is then closed for test relay 45 extending from grounded battery, right winding of said relay, brush 48, terminal 49, back contact and inner armature of relay 50, outer front contact and armature of relay 43 to ground. Energization of relay 45 opens, at its right armature, the circuit for magnet 44 which then ceases to operate and the plungers carried by frame 47 are positioned before the contact springs 85 individual to switch B. The energization of relay 45 also closes an energizing circuit at its left armature and front contact for magnet 51 which operates to engage the several plungers carried by frame 47 with their respective spring contacts. A circuit is then closed for relay 50 from battery through the winding of said relay, spring contact 52, plungers 53 and 54 and spring contact 55 to ground upon the release conductor 42. Relay 50 in attracting its inner armature, opens the original energizing circuit for relay 45 but this relay does not release due to a holding circuit extending from grounded battery, through the left winding of relay 45, plunger 54 and spring contact 55 to ground on the conductor 42. When the several plungers are engaged with their spring contacts, a circuit is also closed for line relay 56 extending from grounded battery, right winding of said relay, plunger 57, contact spring 58, the subscriber's substation apparatus, contact spring 59, plunger 60 and left winding of relay 56 to ground. Relay 56 energizes and establishes a circuit for slow-to-release relay 61 which, in attracting its armature, prepares an energizing circuit for slow-to-release relay 62. The switch is now in condition to receive sets of impulses transmitted from the calling subscriber's substation to step brushes 63, 64 and 65 onto the terminals of the line individual to the called substation 66.

In response to the first deenergization of line relay 56 when the first set of impulses is transmitted, the previously mentioned circuit for slow-to-release relay 62 is closed and this relay in attracting its armature establishes an energizing circuit for escape magnet 67 extending from grounded battery, winding of said magnet, front contact and inner armature of relay 62 to ground. Magnet 67 energizes but does not at this time affect the side switch mechanism in so doing. Each deenergization of line relay 130

56 closes a circuit for the primary stepping magnet 68 extending from grounded battery, winding of said magnet, contact spring 69, plunger 70, side switch wiper 71 in position 1, front contact and armature of relay 61 and back contact and armature of relay 56 to ground. Magnet 68 operates in response to each impulse to step the brushes of switch B to the group of terminals containing those of the called line. At the termination of this first series of impulses, line relay 56 remains energized and thus permanently opens the circuit for slow-to-release relay 62 which, after an interval, releases. Relay 62, in deenergizing, opens the circuit for escape magnet 67 and when this magnet releases the side-switch wipers are all moved to position 2. When the side-switch wiper 45' moves into position 2 and each position thereafter, the same operates to extend another selector switch similar to switch D over a multiple of the common conductor 72. The side switch wiper 45' in moving into position 2 extends the starting conductor 72 to the next idle switch, so that when a connector is seized and its magnet 43 operated the ground applied by the armature of this magnet is transmitted over side switch arm 45' in positions 2, 3 and 4 to the stepping magnet 44 of such switch D. The subscriber at substation 1 then transmits another set of impulses corresponding to the last digit of the wanted line, and in response to each impulse line relay 56 is again deenergized to close the circuit of the secondary stepping magnet 73 extending from grounded battery, winding of said magnet, contact spring 74, plunger 70, side switch wiper 71 in position 2, front contact and armature of relay 61 and back contact and armature of relay 56 to ground. In response to the operation of secondary magnet 73, brushes 63, 64 and 65 are stepped over the terminals of the selected group until those individual to the called substation 66 are reached. At the termination of the second set of impulses, line relay 56 remains energized and opens the energizing circuit for slow-to-release relay 62.

If the called line is busy, this condition will be denoted by ground upon the test terminal 75 and as soon as brush 65 engages said terminal a circuit will be established for test relay 76 extending from grounded battery, left winding of said relay, back contact and outer armature of relay 62, which released after the energizing circuit therefor was opened by line relay 56, side-switch wiper 77, plunger 54, contact spring 78, brush 65 and terminal 75 to ground. It will be noted that escape magnet 67 is made slow-to-release so that after the energizing circuit therefor is opened by the release of relay 62, said magnet will not release before the energizing circuit for test relay 76 has been established, at which time another energizing circuit is maintained for magnet 67 extending to ground, through the inner left armature and front contact at said relay 76. The side-switch wipers will thus be prevented from moving out of position 2 to position 3. When relay 76 is energized, the same is locked up through its right winding, front contact and armature to ground upon the conductor 42 through the plunger 54 and spring contact 55. By attracting its outer left armature, relay 76 applies a busy tone from the apparatus BZ to the calling line in a manner well known in the art and the calling subscriber, upon hearing this busy tone, replaces his receiver upon its switchhook. This will open the circuit for line relay 56 which in turn causes the release of relay 61. A circuit is then established for release magnet 79 extending from grounded battery, winding of said magnet, side switch wiper 80 in position 2, back contact and armature of relay 61 and back contact and armature of relay 56 to ground. Magnet 79 energizes and operates to restore the side switch wipers to normal. Removal of ground from the conductor 42 is accomplished by the replacing of the receiver upon the switchhook at the calling substation and this causes the deenergization of release magnet 43 individual to switch B. The deenergization of magnet 43 returns the brushes 63, 64 and 65 to normal. The holding circuit for relay 45 is also opened by the removal of ground from conductor 42, and relay 45, in releasing, removes ground from its left armature to deenergize magnet 51 which, in so doing, retracts the several plungers from their respective spring contacts. Relay 45, in releasing, also closes at its right armature a self-interrupting circuit for magnet 44 extending to ground through the off-normal contact 81 which was closed upon the first step of wiper 48 from its normal position. Magnet 44 now operates to return the brush carrying frame 47 and wiper 48 to normal position. Upon reaching this position, off-normal contact 81 is opened and magnet 44 ceases to operate, whereupon the switch is in condition to receive another call. Should the calling subscriber abandon the call while the switch is being operated, and the side switch-wiper 80 is in its second, third or fourth positions, the release of the switch will occur in the same manner as above described.

Assuming now that the called substation 66 is idle when the brushes of connector switch B are engaged with the terminals of the called substation line, test relay 76 will remain inert and upon the release of relay 62, at the termination of the second series of impulses, escape magnet 67 will deenergize and move the side-switch wipers to position 3. In this position, ringing current

will be applied to the called line over a circuit extending from the source of ringing current 82, back contact and armature of magnet 67, winding of relay 83, side-switch 5 wiper 84 in position 3, plunger 57, contact spring 85, brush 64, terminal 86, subscriber's substation 66 including the ringer apparatus thereat, terminal 87, brush 63, contact spring 88, plunger 60 and side-switch wiper 89 in 10 position 3 to ground. This ringing current operates a signal at the called subscriber's substation but is not sufficient to energize relay 83 through the winding of which said current passes. When the called subscriber 15 removes the receiver from its switchhook, sufficient current will pass through relay 83 to energize the same, and in attracting its armature, an energizing circuit is established for escape magnet 67 extending from 20 grounded battery, winding of said magnet, side-switch wiper 90 in position 3 and armature and front contact of relay 83 to ground. Magnet 67 operates to move the side-switch wipers from position 3 to position 4, where- 25 upon conversation between the calling and called subscribers may proceed, talking current for the called subscriber's line being supplied in the usual manner by relay 91. The mechanical construction of the side 30 switch whereby it moves its wipers into position 4 upon energization instead of deenergization may be as shown in Fig. 9 of Patent 1,231,013, issued June 26, 1917, to Charles L. Goodrum and described in lines 35 89 to 102 of page 3 of said patent. At the termination of the conversation, the release of the switch is controlled in the same manner as above described when the calling subscriber replaces his receiver upon its switch- 40 hook.

Applicants are claiming in a copending application, Serial No. 315,828, filed August 7, 1919, a circuit arrangement wherein controlling equipments common to a greater 45 number of switches are automatically pre-allotted so as to be temporarily available to a seized trunk to control the same.

What is claimed is:

1. In a telephone system, groups of selector switches, groups of connector switches, impulse relays for each group less in number than the switches thereof and common to such switches, and electromagnetic means automatically actuated upon the seizure of one of said switches for associating an idle impulse relay of the corresponding group with said switch to coöperate in the setting of the same.
2. In a telephone system, groups of selector switches, groups of connector switches, impulse relays for each group less in number than the switches thereof and common to such switches, electromagnetic means automatically actuated upon the seizure of one

of said switches for associating an idle im- 65 pulse relay of the corresponding group with such switch to coöperate in the setting of the same, means for rendering the impulse relay used in setting the selector again accessible to other selectors of its group when 70 said selector is set, and means for rendering the impulse relay used in setting the connector again accessible to other connectors of its group when the called party answers.

3. In a telephone system, groups of selector switches, groups of connector switches, impulse relays for each group less in number than the switches thereof and common to said switches, electromagnetic switches automatically actuated by the seizure of said 75 switches for temporarily associating impulse relays from corresponding groups of impulse relays with such switches, and means whereby the electromagnetic switches and impulse relays revert to common use after 80 the associated switches are set.

4. In a telephone set, groups of selector switches, groups of connector switches, control equipments for each group comprising an impulse relay, a release magnet, slow 90 relays and a side switch, these equipments being less in number than the switches of the group and being common thereto, electromagnetic means automatically actuated upon the seizure of one of said switches for 95 associating an idle equipment of the corresponding group with such switch to coöperate in the setting thereof.

5. In a telephone system, groups of selector switches, groups of connector switches, 100 control equipments for each group comprising a step-by-step switch, an impulse relay, a release magnet, slow relays and a side switch, these equipments being less in number than the switches of the group and being 105 common thereto, and means for causing an idle one of said step-by-step switches to connect its equipment to a switch upon the seizure of such switch, and means whereby the control equipments revert to common use 110 after the corresponding switches are set.

6. In a telephone system, a subscriber's line, groups of selector switches, groups of connector switches, impulse relays for each group less in number than the switches thereof and common to such switches, electromagnetic means automatically actuated upon the seizure of one of said switches for associating an idle impulse relay of the corresponding group with such switch to coöperate in the setting of said switch, and a dial 115 associated with said subscriber's line for actuating said impulse relays in succession.

In witness whereof we hereunto subscribe our names this 4th day of August, A. D. 125 1919.

JAMES L. McQUARRIE.
CHARLES L. GOODRUM.
